UNITED STATES PATENT OFFICE.

GRANVILLE H. STALLMAN, OF CINCINNATI, OHIO, ASSIGNOR TO THE C. SCHMIDT COMPANY, OF CINCINNATI, OHIO, A CORPORATION OF OHIO.

HOG-SCRAPER.

1,101,155.

Specification of Letters Patent. Patented June 23, 1914.

Application filed July 21, 1912. Serial No. 720,370.

To all whom it may concern:

Be it known that I, GRANVILLE H. STALLMAN, a citizen of the United States, residing at Cincinnati, in the county of Hamilton and State of Ohio, have invented certain new and useful Improvements in Hog-Scrapers, of which the following is a specification.

My invention relates to improvements in hog scraper mechanism.

One of its objects is to provide improved supporting and discharging mechanism.

Another object is to provide an improved combination of supporting and cleaning mechanism.

Another object is to provide improved discharge releasing mechanism.

My invention also comprises certain details of form, combination, and arrangement, all of which will be fully set forth in the description of the accompanying drawings, in which:

Figure 1 is a side elevation partly in section of my improved mechanism. Fig. 2 is a top plan view of the same with parts broken away. Fig. 3 is a sectional detail of a portion of the releasing mechanism. Fig. 4 is a perspective detail of a portion of the latch mechanism detached. Fig. 5 is a perspective view of another portion of the latch mechanism. Fig. 6 is a detail side elevation of one of the cleaners detached. Fig. 7 is a perspective view of one of the stationary supporting members detached. Fig. 8 is a perspective view of one of the movable supporting members detached.

The accompanying drawings represent the preferred embodiment of my invention, in which A represents the frame of the machine, B represents the scalding tank, and C the table on which the cleaned hogs are automatically discharged. The hogs are elevated one at a time from the scalding vat by means of a series of chain belts 2, each

45 provided with a single conveyer tooth 3. Said belts 2 are mounted at one end upon sprocket wheels 4 carried by a shaft 5 journaled in brackets 6 attached to the bottom of the vat B, and at the opposite end upon sprocket wheels 7 mounted upon a shaft 8

50 journaled to the sub frame 9.

The conveyer belts 2 deposit the hogs upon a supporting frame composed of a series of stationary bars 10 and a series of

55 pivotally supported movable bars 11, in

line with said stationary bars, which together constitute a supporting cradle with an inclined section leading from the shaft 8 to the depressed or central portion of said cradle. The bars 10 and 11 of the cradle 69 are spaced apart to permit cleaners or beaters to act upon the hog through the intermediate spaces, and said bars serve to hold the hog in the desired position to be acted upon by the cleaners while the action of the 65 cleaners upon the hog causes the hog to rotate upon the supporting bars to expose all portions of its body to the action of the cleaners. After the hog has been subjected sufficiently to the action of the cleaners, 70 latch mechanism holding the bars 11 in position is automatically tripped, allowing the bars 11 to swing out away from the bars 10, and permitting the hog to descend by gravity to the receiving table C. 75

The cleaner mechanism may be variously modified, but as illustrated, comprises a series of hubs 14 rigidly mounted upon the shafts 15 and 16 intermediate of the bars 10 and 11, and to which are attached a 80 series of cleaners or beaters 17 each formed by looping a section of canvas bedding or similar semi-flexible material and uniting its opposite ends at 12. These loops may be armed with metal spurs 18, and are detachably clamped in recesses formed in the periphery of the hubs by means of clamping plates 19 bolted to the hubs. The cleaners 17 are preferably of a width to occupy practically all of the space between the adjacent bars 10 and 11, and thereby tend to prevent the legs of the hog from entering between the bars and becoming broken or damaged. 85

The shaft 15 is journaled stationarily to 90 the frame A, and is provided at one end with tight and loose pulleys 20 and 21 for the application of power. Power is transmitted from shaft 15 to a shaft 22 stationarily journaled to frame A by means of a 100 chain belt 24 and sprocket wheels 25 and 26. The shaft 22 serves as the support for and center on which the arms 11 pivot or swing, and the shaft 16 is journaled in bearings carried by the arms 11, and moves with the 105 arms 11. Power is transmitted from shaft 22 to shaft 16 by means of a chain belt 27 and sprocket wheels 28 and 29, so as to drive the shaft 16 in the same direction and at practically the same speed as shaft 110

15, thus causing the hog to rotate upon the supports 10 and 11 at a slower rate than the cleaners on shafts 15 and 16, due to the action of the cleaners upon the hog.

5 Power is transmitted from the shaft 22 to an idler shaft 30 by means of a chain belt 31 and sprocket wheels 32 and 33. The shaft 34 is driven in the reverse direction to that of shaft 30 and at a slower rate by 10 means of a pinion 35 on shaft 30 and gear 36 on shaft 34. Power is transmitted from shaft 34 to the elevator shaft 8 by means of a chain belt 37 and sprocket wheels 38 and 39.

15 Sprocket wheels 40 are rigidly mounted on short shafts 60 journaled to frame A. Said wheels 40 are driven from sprocket wheels 42 on shaft 34 by means of chain belts 43, preferably to cause the wheels 40 to rotate in the same period with the elevator hooks 3. The wheels 40 are provided with crank pins 44 which rotate about the axis of wheels 40 and periodically engage levers or crank arms 45 on the short shafts 46. Said shafts 46 are journaled in boxes at opposite ends of the frame A and each at its opposite end carries rigidly a latch or hook 48 to engage a stud H carried by the end or outside bar 11. Thus the bars 11 which are all tied or locked together by the stay rod 47, and also by the shafts 22 and 16, are engaged by the latches 48 and locked in position with their lower ends engaging the knees h of the bars 10 until such time as the crank pins 44 engage the arms 45 to rock the shafts 46 and lift said latches 48, whereupon the arms 11 and shaft 16 due to the weight of the hog, swing away from the arms 10 and shaft 15 and permit 40 the hog to descend by gravity to the table C. After the arms 11 are relieved of the weight of the hog, they swing back into position and are reengaged by the latches 48 and the machine is in position to receive another 45 hog from the elevator hooks 3, the movements of which are timed to deliver another hog immediately after the arms 11 have returned to position.

In order to provide for the arms 11 coming back to the locked position with certainty, and without unnecessary shock, I preferably provide one or more pivoted arms 50 provided with adjustable weights 51, and attached by links 52 to the arms 11, 55 and which may be adjusted to the right or left of their fulcrums to properly counter-balance the arms 11 and cleaner shaft 16 so that they will return to position but without unnecessary shock.

60 In order to compensate for variation in the weight of different hogs, and avoid the arms 11 returning to the position to be latched with too great force, I preferably also mount the wheels 40 upon short shafts 60 journaled to opposite sides of frame A

and on the inner ends of said shafts mount crank arms 61 carrying pins 62 which as the arms 11 return toward latching position engage cam plates 63 carried by the end bars 11 and hold the bars 11 out from bars 10 a sufficient interval of time to insure the hog being discharged to the feed table and then as the pins 62 and cams 63 are about to disengage ease the bars 11 gently to latching position.

In practice the hog as soon as it leaves the elevator hooks 3 slides down the inclined face 65 of the bars 10 to a position upon the bars 10 and 11 above and between the cleaners on shafts 15 and 16 where it rotates slowly for a short period, say twenty to thirty seconds, whereupon the latches are tripped, the hog discharged and a fresh hog fed in from the elevator. The supporting bars being in line with each other there is no opportunity for the hog to become caught or injured, and the cleaners occupying practically all the space between the supporting bars prevent the legs or projecting parts getting between the bars and cleaners or in position to be cut or injured, and the hog resting upon the bars and rotating thereon is in position to be cleaned over the entire surface, as there is sufficient movement of the hog endwise to enable the cleaners to reach all parts.

A pipe 66 is perforated with a row of holes and supplied with water which is sprayed over the hog during the cleaning operation. The scurf etc., falls upon the inclined fenders 67 and 68, and is directed therefrom into a receiver below, which is not shown.

Tie-rods 70 and 71 are employed to support and space the bars 10 relative to the frame A.

The mechanism herein illustrated is capable of considerable modification without departing from the principle of my invention.

Having described my invention, what I claim is:

1. A hog scraper comprising a series of stationary supporting bars, a series of pivotally mounted supporting bars in line with said stationary bars and movable to and from said stationary bars to form an opening for the ejection of the hogs, and cleaner mechanism supported below said supporting bars and engaging the hogs through the spaces between said supporting bars.

2. A hog scraper comprising rotary horizontal cleaners and means to support the hogs above said cleaners comprising independently mounted spaced bars substantially parallel and arranged to periodically open to eject the hogs.

3. A hog scraper comprising a plurality of substantially horizontal cleaner shafts armed with rotary cleaners, and means to support the hogs above said cleaner shafts.

- comprising spaced inclined stationary bars and spaced pivotally supported bars in line with said stationary bars and arranged to periodically form an opening between said 5 respective sets of bars to eject the hogs.
4. A hog scraper comprising a hog elevator, a series of spaced inclined stationary bars to receive the hogs from said elevator, a series of spaced pivotally mounted bars in 10 line with said stationary bars to form with said stationary bars a cradle to support the hogs and to periodically form an opening to eject the hogs, a stationarily mounted cleaner shaft below said stationary bars armed with 15 rotary cleaners to engage the hog through spaces between said stationary bars, and a cleaner shaft mounted to move with said pivotally mounted bars and armed with rotary cleaners to engage the hogs through 20 spaces between said pivotally mounted bars.
5. A hog scraper comprising a hog elevator, a series of spaced inclined stationary bars to receive the hogs from said elevator, a series of spaced pivotally mounted bars in 25 line with said stationary bars to form with said stationary bars a cradle to support the hogs and to periodically form an opening to eject the hogs, a stationarily mounted cleaner shaft below said stationary bars armed with 30 rotary cleaners to engage the hog through and occupy substantially all the space between said respective stationary bars, and a cleaner shaft mounted to move with said pivotally mounted bars and armed with rotary 35 cleaners to engage the hogs through and occupy substantially all the space between said respective pivotally mounted bars.
6. A hog scraper comprising a hog elevator, a series of spaced inclined stationary bars to receive the hogs from said elevator, a series of spaced pivotally mounted bars in 40 line with said stationary bars to form with said stationary bars a cradle to support the hogs and to periodically form an opening to 45

eject the hogs, a stationarily mounted cleaner shaft below said stationary bars armed with rotary cleaners to engage the hog through spaces between said stationary bars, a cleaner shaft mounted to move with said pivotally 50 mounted bars and armed with rotary cleaners to engage the hogs through spaces between said pivotally mounted bars, and latch mechanism to engage and periodically release said pivotally mounted bars in period with 55 the movements of said hog elevator.

7. A hog scraper comprising a hog elevator, a series of spaced inclined stationary bars to receive the hogs from said elevator, a series of spaced pivotally mounted bars in 60 line with said stationary bars to form with said stationary bars a cradle to support the hogs and to periodically separate therefrom to form an opening to eject the hogs, a stationarily mounted cleaner shaft below said 65 stationary bars armed with rotary cleaners to engage the hog through spaces between said stationary bars, a cleaner shaft mounted to move with said pivotally mounted bars and armed with rotary cleaners to engage 70 the hogs through spaces between said pivotally mounted bars, latch mechanism to engage and periodically release said pivotally mounted bars in period with the movements of said hog elevator, and means to ease the 75 return of said pivotally mounted bars to latched position.

8. A hog scraper comprising a series of spaced bars to support a hog in substantially horizontal position, rotary cleaners upon a 80 horizontal axis below said bars to contact with the hog through the spaces between said bars, and intermittently operated means to eject the hog from said supporting bars.

In testimony whereof I have affixed my 85 signature in presence of two witnesses.

GRANVILLE H. STALLMAN.
